SMOKE-TUBE SUPERHEATER.

1,073,305.

Specification of Letters Patent. Patented Sept. 16, 1913.

Application filed October 29, 1912. Serial No. 722,594.

To all whom it may concern:

Be it known that we, PETER THOMSEN and EGMONT DOETTLER, subjects of the King of Prussia, Emperor of Germany, residing at Cassel, Germany, have invented a certain new and useful Improvement in Smoke-Tube Superheaters, of which the following is a specification.

Our invention relates to smoke tube superheaters and particularly to those for locomotives.

Under certain conditions of working, for instance, when the engine is stopped and when the boiler is fired up, difficulties arise in connection with overheating of the superheater pipes because at such times they are not cooled by the passing steam and it is the object of the present invention to overcome these difficulties. To attain this purpose a pipe is led from the superheated steam header through which pipe the steam can be led to the blower of the locomotive, a shutting-off device being arranged at the outlet-aperture of the superheated steam header which closes the latter when the steam supply to the engine shall be shut off.

The accompanying drawing illustrates an example of one form of the present invention in which a controlling valve is arranged at the steam chamber of the superheater so as to allow the engine to work either with superheated steam, with saturated or with mixed steam.

Figure 1 shows a sectional view through the superheater, the controlling valve being set to allow the engine to be worked with superheated steam. Fig. 2 shows the position of the valve when shutting off the passage of steam to the engine; Fig. 3 shows the valve so placed that a part only of the boiler steam passes through the superheater, the remainder going to the engine direct.

In the accompanying drawing, *a* is the steam space of the locomotive boiler, *b* the smoke tubes and *l* the superheater tubes. The saturated steam ends of the superheater tubes are expanded into the bottom wall of a chamber *h* and the superheated steam ends are connected to an adjoining chamber *i*. The chamber *h* represents the saturated steam header and the chamber *i* the superheated steam header of the superheater. The steam enters the saturated steam header,

as shown by the arrows, by way of the port *e* and leaves the superheated steam header by way of the port *f* in order to be led to the engine through the chamber *h*, the port of which is indicated at *g*. The course of the steam can be controlled by operation of the rotary valve which comprises the valve chamber *d* and the arched valve member *n* with terminal flanges *o*.

In accordance with the present invention a steam pipe *m* is led from the superheated steam header *i* by means of which superheated steam passes to the blower. The steam pipe *m* is provided with a controlling valve (not shown) so that the flow of steam may be regulated or stopped as required.

In the example illustrated, the controlling valve *d* can itself be used as the regulator (main shutting-off device). It is advisable, however, to supply the usual regulator in addition, as the controlling valve may then be more easily adjusted. Care should however be taken that the regulator is closed before adjusting the controlling valve.

The operation of the device described is as follows: With the controlling valve as shown in Fig. 1 steam from the boiler passes through the port *e* into the saturated steam header *h* and thence through the superheating tubes into the superheated steam header *i* and so through the port *f*, the arch *n*, and the port *g*, into the chamber *h* and so to the cylinders. In Fig. 2 the valve member *n* has been moved so that its flange *o* covers the port *f* of the superheated steam header. The passage of superheated steam to the engine is thus shut off. As the port *e* of the saturated steam header however is open to the boiler the superheater is full of steam and when the shut-off device of the auxiliary pipe *m* is opened steam can be led away to the blowers. In this way when the locomotive is stationary or especially when the boiler is started, a flow of steam is insured through the superheater tubes which are thus prevented from overheating. Fig. 3 shows the position of the valve member *n* in which a part only of the steam passes through the superheater the remainder passing direct into the chamber *h* and so to the cylinders.

Although the primary use of the auxiliary pipe *m* is to insure a circulation of steam

through the superheater tubes when the steam to the cylinders is shut off, nevertheless it will be seen that steam may also be drawn through the auxiliary pipe *m* even when 5 steam is passing to the cylinders.

- It will be evident that the details of the present invention such as the form and arrangement of headers or collectors, superheating tubes and controlling valves may 10 be varied to a very large extent without departing from the feature of taking superheated steam for the blower so as to insure a circulation through the superheater tubes.

According to the present invention the 15 superheater tubes are cooled just by that steam which causes a danger to the superheater tubes when the fire is blown up.

Having described our invention, we claim:

1. In a locomotive provided with a blower 20 and smoke tube superheater of the class described, the combination of a superheated steam header having steam connection with the engine cylinders, a valve for closing off said steam connection, and an outlet from 25 said header between the valve and the superheater elements connected to the blower.
2. In a locomotive provided with a blower 30 and smoke tube superheater of the class described, the combination of a saturated steam header having steam connection with the boiler, a superheated steam header having steam connection with the engine cylinders, a direct connection between the boiler and the cylinders, a valve controlling said 35 three connections and adapted to simultaneously close the connection between superheated header and engine cylinders and the direct connection between boiler and engine cylinders, and an outlet from the superheated header between the valve and the 40

superheater elements connected to the blower.

3. In a locomotive provided with a blower and smoke tube superheater of the class described, the combination of a valve having 45 ports connected respectively with the boiler, the saturated steam header, the superheated steam header and the engine cylinders and provided with a valve member arranged to simultaneously close the ports of the superheated header and of the engine cylinders, with the superheated header said header being provided with a blower outlet between 50 the valve chamber and the superheater elements. 55

4. In a locomotive provided with a blower and smoke tube superheater of the class described, the combination of a valve having 60 ports arranged one after the other and connected respectively with the boiler, the saturated steam header, the superheated steam header and the engine cylinders, the width of the three last named ports being substantially the same while that of the first named port is substantially greater, said valve being further provided with an arched valve member having terminal flanges wide enough to close the three last named ports but not the first named port, with the superheated header, said header being provided 65 with a blower outlet between the valve chamber and the superheater elements. 70

In testimony whereof, we have hereunto set our hands in the presence of two subscribing witnesses.

PETER THOMSEN.
